UNITED STATES PATENT OFFICE.

PERRY BROWN, OF CORAOPOLIS, PENNSYLVANIA.

JOURNAL-BOX.

1,171,087.

Specification of Letters Patent. Patented Feb. 8, 1916.

Application filed October 28, 1914. Serial No. 869,133.

To all whom it may concern:

Be it known that I, PERRY BROWN, a citizen of the United States, and a resident of Coraopolis, in the county of Allegheny and State of Pennsylvania, have invented certain new and useful Improvements in Journal-Boxes, of which the following is a specification.

This invention relates to improvements in journal boxes and more particularly to the device for locking the lid closed.

While my invention may be applied to various forms of boxes, I have illustrated it in connection with a box of the character shown in my Patent No. 649,535.

The invention consists in the locking device hereinafter described and the preferable embodiment of which is illustrated in the drawings accompanying and forming part hereof.

In said drawings, comprising two sheets: Figure 1 is a perspective view of part of a box with my invention applied thereto. Fig. 2 is a vertical section through the locking device. Fig. 3 is a top plan view of the corner of the box. Fig. 4 is a perspective view of the box with the lid open. Figs. 5 and 6 are views of a modified form.

Referring now to the details of the drawings by numerals: 1 designates the end of a journal box of any desired construction to which a lid 2 is pivoted by means of the hinge joint 3. The lid is so arranged that it may be thrown open as shown in perspective view in Fig. 4 or it may be closed as shown in Fig. 1. At the side of the feed opening opposite the hinge 3 the box is formed with a lug 4 having an inclined upper surface 5 and its lower edge beveled or rounded as indicated at 6 in Fig. 2. The extreme corner of the lid 2, opposite the hinge 3, is provided with a combined locking and lifting device comprising a plate 8 which is pivoted to a lug 10 cast integrally with the lid 2, a pin 12 passing through the lug 10 and a boss 14 projecting from the rear of the upper end of the plate 8. The plate 8 is also provided with a handle 16 preferably of the construction shown in the drawings, whereby the operator may place a waste hook or other implement under the handle 16 and move the same slightly upon the pivot 12 as will be hereinafter explained. The lid is provided with an opening or recess 20, shown best in Fig. 2, and the plate 8 is provided with a latch 22 which is arranged

to project through the opening or recess 20 and, when the lid is in the closed position, swing under the beveled or rounded part 6 of the lug 4, as will be seen from an inspection of Fig. 2.

Thus when the parts are in the positions shown in full lines in Fig. 2, the latch 22 of the plate 8 will project through the opening or recess 20 of the lid 2 and be located under the lug 4 so as to lock the lid 2 in its closed position. When, however, the operator places any kind of an implement under the handle 16 and lifts the implement, the first movement will be to draw the handle 16, its plate 8 and the latch 22 from the position shown in full lines in Fig. 2 to the position shown in dotted lines in Fig. 2. Thus the latch 22 will be released from the lug 4 and further upward movement of the operator's implement under the handle 16 will lift the lid from the position shown in Fig. 1 to the position shown in Fig. 4. In order to permit the movement of the plate 8 as just described, either the front side of the lug 10 or the rear side of the plate 8 is cut slightly away. As illustrated in the drawings, the front side of the lug 10 is cut away as indicated at 24. This not only permits the handle 16 and its plate 8 to be swung in the position shown in dotted lines in Fig. 2 but the inclined edge 24 acts as a stop to prevent further movement of the plate 8 on its pivot 12. I desire to call attention to the fact that the upper surface of the latch 22 is formed on an arc drawn from the center of the pin 12 and that the curvature of the lower part 6 of the lug 4 is formed of the same curvature so that when the latch 22 is in position, it cannot be moved out of position by any tendency of the lid to shake upward on its pivot 3. At the same time, any movement tending to draw the handle 16 on its pivot 12 will cause the plate 8 and its latch 22 to swing on an arc on which the pin 12 is the center and thus the latch 22 can easily be released from the beveled or curved bottom 6 of the lug 4.

If, in the operation, the attendant should leave the lid in the open position shown in Fig. 4 as soon as the cars start or are given any shaking motion whatever, or as soon as coupling of the cars takes place, the lid will be vibrated from the balanced position shown in Fig. 4 so that it will fall and thus close itself. My locking device forms no obstruction to the complete automatic clos-

ing of the lid for there are no heavy springs to operate in closing, but all that the lid has to do is to move the plate 8 slightly upward as the lower beveled edge 23 of the latch 22 5 strikes against the other beveled edge 5 of the lug 4 shown in Fig. 4.

A modified form of my locking and lifting device is shown in Figs. 5 and 6. In this modified form the lid is formed with a casing 30 within which may be pivoted a locking and lifting device 32 very similar to that shown in Figs. 1 to 4 inclusive. This combined locking and lifting device 32 has a handle 34 projecting outside of the casing 10 30 and a latch 36 projecting from the inner side of the casing 30 to co-act with a lug 38 on the body of the box substantially identical with the lug 4 shown in Figs. 1 to 4. In this construction, when the operator 15 moves the handle 34, the latch 36 will be withdrawn to the left, as viewed in Fig. 6, and the inside of the casing 30 will act as a stop to prevent too much movement of the latch 36, so that the inside of the casing 20 30 performs the same function as the cut away portion 24 illustrated in Fig. 2.

From the foregoing and accompanying drawings it will be seen that I have provided a very simple form of locking and lifting 30 device which can be added with practically no additional cost and which cannot possibly get out of order and at the same time the device will automatically lock the lid as the lid falls to its closed position.

35 It will be obvious that changes and modifications may be made in my invention without departing from the spirit thereof, the scope of which is set forth by the appended claims.

40 What I claim as my invention is:

1. In a journal box, a box proper, and a lid closing the feed opening of the same, said lid having a latch pivotally supported thereon normally dropping by gravity substantially parallel with the lid, the latch swinging at right angles to the lid under a 45 part of the box as the lid closes, whereby the latch locks the lid to the box, substantially as described.

50 2. In a journal box, a box proper, and a lid closing the feed opening of the same, said lid having a latch pivotally supported thereon normally dropping by gravity substantially parallel with the lid, the latch 55 swinging at right angles to the lid under a part of the box as the lid closes, thereby locking the lid to the box, and a handle projecting from said latch whereby when said handle is moved the latch moves on its pivot to release the lid, substantially as described.

60 3. In a journal box, a box proper, a lid closing the feed opening of the same, a plate pivotally supported on said lid and having a latch normally hanging substantially parallel with the lid and swinging at right 65

angles to the lid, under a part of the box as the lid closes, and a handle projecting from said plate whereby when said handle is moved, the plate is moved on its pivot to release the latch from the box, substantially as described. 70

4. In a journal box, a box proper having a lug thereon, a lid closing the feed opening of said box, and a plate pivotally supported by said lid and having a latch normally hanging substantially parallel with the lid and movable at right angles to the lid, said latch striking the upper part of said lug just before the lid closes and swinging under said lug as the lid reaches its closed position, 75 substantially as described.

5. In a journal box, a box proper having a lug thereon, a lid closing the feed opening of said box, a plate pivotally supported by said lid and having a latch normally hanging substantially parallel with the lid and movable at right angles to the lid, said latch striking the upper part of said lug just before the lid closes and swinging under said lug as the lid reaches its closed position, 80 and a handle projecting from said plate whereby when said handle is moved the plate moves on its pivot to release the latch from said lug, substantially as described. 85

6. In a journal box, a box proper having a lug thereon, and a lid closing the feed opening of the same, said lid having a latch pivotally supported thereon and normally hanging substantially parallel with the lid, the latch swinging at right angles 90 to the lid under said lug as the lid closes, and a stop limiting the movement of the latch as the lid is opened, substantially as described. 95

7. In a journal box, a box proper having a beveled lug thereon, a lid closing the feed opening of said box, and a plate pivotally supported on said lid and having a latch normally hanging substantially at right angles to the lid and swinging against said beveled lug at right angles to the lid as the lid closes, said latch moving by gravity under the lug, substantially as described. 105

8. In a journal box, a box proper having a beveled lug thereon, a lid closing the feed 110 opening of said box, a plate pivotally supported on said lid to move at right angles to the lid and having a latch swinging against said beveled lug as the lid closes, said latch moving by gravity under the lug, 115 and a handle projecting from said plate whereby when said handle is moved the plate is moved on its pivot to release the latch from its lug, substantially as described. 120

9. In a journal box, a box proper having a lug thereon, a lid closing the feed opening of the same and having an opening or recess therein, a plate pivotally supported on said lid and having a latch swinging 125

through said opening or recess and co-operating with said lug, and a handle projecting from said plate whereby when said handle is moved the plate is swung on its pivot to release the latch from the box, substantially as described.

10. In a journal box, a box proper having a lug with a beveled upper surface and a beveled or curved under surface, a lid closing the feed opening of said box and having an opening or recess therein, and a plate pivotally supported by said lid and having a latch swinging through said opening or recess and co-acting with the beveled lug 15 on the box, substantially as described.

11. In a journal box, a box proper having a lug with a beveled upper surface and a beveled or curved under surface, a lid closing the feed opening of said box, a plate 20 pivotally supported by said lid and having a latch normally hanging substantially parallel with the lid and co-acting with said lug, the latch moving at right angles to the lid against the beveled upper surface 25 of the lug as the lid is nearly closed and sliding under the lug as the lid reaches its closed position, substantially as described.

12. In a journal box, a box proper having a lug thereon, a lid closing the feed

opening of the box and having an opening 30 or recess therein, a plate pivotally supported on said lid and having a latch swinging out of the opening or recess and co-operating with said lug, said lid having a casing covering said plate, and a handle on 35 said plate projecting through said casing, whereby when said handle is moved the plate is swung on its pivot to release the latch from the box, substantially as described. 40

13. In a journal box, a box proper having a lug thereon, a lid closing the feed opening of the box, a vertically disposed plate pivoted at its upper end to said lid and having a latch co-acting with the lug on said box, said vertically disposed latch swinging on its pivot at right angles to the lid as it strikes said lug when the lid is nearly closed and sliding under the lug as the lid reaches its closed position, substantially as described. 45 50

In testimony whereof I affix my signature in presence of two witnesses.

PERRY BROWN.
